DESIGN FOR A COAT

Max Moshansky, New York, N. Y.

Application September 24, 1936, Serial No. 64,989

Term of patent 3½ years

To all whom it may concern:

Be it known that I, Max Moshansky, a citizen of the United States of America, residing in borough of Bronx, county of Bronx, city and State of New York, have invented a new, original, and ornamental Design for a Coat, of which the following is a specification, reference being had to the accompanying drawing, forming part thereof,

Fig. 1 is a front view of a coat showing my new design.

Fig. 2 is a rear view of the coat shown in Fig. 1.
I claim:

The ornamental design for a coat substantially as shown.

MAX MOSHANSKY.
